OIL-WELL PUMP

Application filed July 5, 1927. Serial No. 203,512.

My invention relates to pumps for elevating liquids, and particularly, although not necessarily, to pumps for elevating oil from wells.

It is a purpose of my invention to provide a pump for elevating oil from wells which is characterized by the employment of any fluid other than a liquid placed under pressure and permitted to expand in such relation to the oil within the well as to subject the latter to a series of lifting impulses in a successive ascending order, whereby the oil is caused to flow from the well.

It is also a purpose of my invention to provide an oil well pump in which the expulsion of a combustible gas is employed and controlled to occur successively in the chambers of a plurality of pumping units so as to displace bodies of oil successively from one chamber to the next chamber above until they are finally ejected from the well.

I will describe only two forms of oil well pumps embodying my invention and will then point out the novel features thereof in the claims.

In the accompanying drawings:

Figure 1 is a view showing schematically and partly in section one form of oil well pump embodying my invention.

Fig. 2 is a view similar to Fig. 1 showing schematically and partly in section a modified form of pump embodying my invention.

Fig. 3 is a fragmentary, vertical and sectional view showing a modified form of pumping unit having a relief valve and embodying my invention.

In the drawings and particularly in Fig. 1, my invention in its present embodiment is shown as comprising a pump barrel designated generally at B, which is tubular in form and of such length that when placed within a well casing K, as illustrated in Fig. 1, its lower end will be submerged within the oil, and its outer end projected from the top of the well. The barrel B is made in sec-

tions connected in end to end relation so as to be disposed one above the other, and each section constitutes a pumping unit which, through the employment of an expansible fluid, operates to displace oil therefrom and into the next unit above. The lowermost or inlet pumping unit comprises a barrel section 15 provided at its lower end with an inlet port 16 through which the passage of oil is controlled by a valve 17 in such a manner that oil is free to enter the barrel section from the well casing, but it cannot be discharged from the barrel section through the port.

The upper end of the barrel section 15 is defined by a partition 18 which separates the barrel section from the next one above. Communication between the two barrel sections is effected, however, through the provision of a tube 19 which extends downwardly from the partition 18 into the barrel section 15 and is at its lower end provided with an inlet port 20 controlled by a valve 21, to prevent descension of oil therein but to permit ascension of oil from the barrel section 15 upwardly into the barrel section 22 of the next pumping unit. At the upper end of the barrel section 15, adjacent to the partition 18, is a fluid inlet port 23 controlled by a valve 24, the stem of which is engageable by a notched cam member 25 fixed to the upper end of a rod 26, freely movable within the barrel section 15, and through a float 27 disposed in the barrel section and in surrounding relation to the tube 19. Spaced stops 28 and 29 are fixed to the rod 26 and form abutments for the float 27 in a manner to cause the float in its vertical movements to actuate the cam member 25 so as to move the latter into or out of engagement with the valve 24 and thus to open or close the latter. With the float 27 in the elevated position shown in Fig. 1 it engages the upper abutment 28, thereby lifting the cam 25 to engage and secure the valve 24 in open position. In

the lowermost position of the float it engages the abutment 29, thus lowering the cam 25 out of engagement with the valve 24 so as to permit the latter to move to closed position.

5 The port 23 communicates with a fluid supply pipe 30 which extends upwardly at the outer side of the barrel B to the top of the well where it is adapted for communication with a source of fluid supply, as will be described hereinafter. By the provision of this pipe 30 and suitable mechanism, an expansible fluid is supplied to the barrel section 15 in a manner to displace the oil contained therein and thus cause the latter to be ejected from the barrel section through the tube 19 into the barrel section 22 of the next unit above. In this operation the pressure imposed upon the oil closes the inlet valve 17 and opens the valve 20 so as to prevent ejection of oil from the port 16 and to permit the oil to be expelled through the tube 19. As the oil is expelled, the float 27 descends and thereby engages the abutment 29, thus actuating the cam 25 in order to permit closing of the valve 24 so that further supply of the pressure fluid to the barrel section 15 is temporarily discontinued.

30 The construction and operation of all of the other pumping units are identical with the barrel section 15, except of course, that they are not provided with inlet valves 17. The barrel sections of the other units are designated 22, 31, 32, and 33, the latter section being the uppermost one and provided 35 with an outlet pipe 34 from which the oil is ultimately discharged at a point above the top of the well. Pressure fluid is adapted to be supplied to the barrel sections of these units through branch pipes 35, 36, and 37, respectively, in communication with the main supply pipe 30.

40 In the present embodiment of my invention I employ a combustible gas, such as gasoline vapors, as the pressure fluid for displacing oil successively upward from the lowermost pumping unit, and through the provision of suitable means charges of this combustible gas are intermittently supplied to the pipe 30, as exploded by ignition, and 45 then exhausted. The three operations constitute a cycle and by the said means the cycle of operation is effected and repeated indefinitely and automatically so as to produce, in effect, a continuous pumping of oil from the well.

50 The means in the present instance comprises a valve V rotatable in a casing C and provided with an L-shaped port 38, the ends of which are adapted to register with casing ports 39, 40 and 41, the latter port being in communication with an exhaust pipe 42. The port 39 communicates with the supply pipe 30, while the port 40 communicates with an intake pipe 43 connected with a suitable 55 carburetor 44 to which air under pressure

is supplied from a tank 45 by a pipe 46, and gasoline or any other suitable combustible fluid is supplied from a tank 47 through a pipe 48. An air pump 49 is provided for supplying air under pressure to the tank 70 45.

75 The valve V is rotatable in a clockwise direction, as indicated by the arrow, by means of an electric motor M having a worm 50 meshing with a worm wheel secured to the valve in any suitable manner. A conducting ring 53 is fixed to the valve for rotation therewith, and this ring is provided at intervals with segments 53, 54, and 55, of insulating material. These segments are 80 at their outer sides exposed to the periphery of the ring. A contact arm 57 extends radially from the ring 52 for bridging a pair of stationary contacts 58^a constituting the terminals of a circuit for a spark plug 58 disposed to produce a spark within the pipe 30 for igniting the gas charge therein. This ignition circuit is supplied with current from a generator G, the latter also being employed 85 to supply current to the motor M.

90 The circuit for the motor M includes a pair of spring contact arms 59 and 60, both of which are positioned to bear on the periphery of the conducting ring 52 or the insulating segments 53, 54, and 55, depending 95 upon the position of the conducting ring, as will be understood. The motor circuit also includes a pair of contacts 61 and 62 electrically connected by a wire 63 and positioned on the dial of a pressure gauge 10 100 so as to be engaged by the indicating hand 64 thereof, according as the hand moves in one direction or the other. This gauge is in communication with the pipe 30, the contact 62 being located at the zero point on the 105 dial of the gauge, and the contact 61 being located at a certain point on the dial, so as to register a predetermined pressure above 110 zero of the fluid in the pipe, and the hand being allowed to continue rotation in a clockwise direction beyond the contact 61 so as to be out of contact therewith when the pressure in the pipe 30 exceeds the pressure indicated on the dial at the contact 61.

115 The operation of the pump is as follows:

When the pump barrel is lowered into the well, oil enters and fills the barrel section 15 through the port 16, thus elevating the float 27 to the position shown in Fig. 1 and thereby lifting the cam 25 so as to secure the valve 24 in open position. It being assumed that the generator G is operating and thus, when the spring contacts 59 and 60 are in engagement with the ring 52, causing rotation of the motor M and consequently 125 rotating the valve V to the position shown in Fig. 1, so that the pipes 30 and 43 thereby come in communication with each other, it is apparent that the combustible gas mixture from the carburetor 44 will be supplied to 130

the barrel section 15. This mixture continues to be supplied to the barrel section until the pressure thereof is such that the hand 64 of the gauge comes into engagement with the contact 61. As soon as the valve has been rotated to its position for establishing communication between the pipes 30 and 43, the valve is stopped, since the motor circuit is broken between the spring contacts 59 and 60 by the insulating segment 53. However, since both the hand 64 and the contact 61 are in the circuit for the motor M, it is clear that, as soon as the hand engages the contact, the motor is again energized, thus setting the valve V and the conducting ring 52 into rotation. The movement of the valve V is such as to disconnect the pipe 43 from the pipe 30, while the movement of the conducting ring is such as to cause the contact arm 57 to bridge the contacts 58^a and thereby close the ignition circuit. The spark occurring at the plug 58 ignites the gas in the pipe 30 and the barrel section 15 thereby producing a relatively high pressure, which operates to expel the oil from the barrel section upwardly through the tube 19 into the barrel section 22, and at the same time causes the hand 64 to rotate beyond the contact 61, as before described. It is important to note that the engagement of the hand 64 with the contact 61 is only momentary but sufficient to initiate energization of the motor M. Such energization causes the motor to rotate the ring 52 sufficiently to move the insulating segment 53 out of engagement with the contact arms 59 and 60, thereby completing the circuit for the motor through the contact arms and the conducting ring 52, as will be understood. Thus, the motor continues to operate until the next insulating segment 54 engages the spring contact arm 59 so as to disrupt the motor circuit and thus discontinue further rotation of the conducting ring. By such an operation, the ring, together with the valve V, is moved through an arc of substantially 45°, and this movement is sufficient to close the end of the pipe 30 and cause the contact arm 57 to bridge the contacts 58^a. Following an explosion of the gas mixture within the barrel section 15, its pressure gradually decreases and consequently causes the hand 64 to return to its former position in engagement with the contact 61, thus again completing the motor circuit and thereby setting the motor into operation so as to produce further initial rotation of the valve V and the conducting ring 52. As in the first instance, such initial rotation of the ring 52 is sufficient to displace the insulating segment 54 from engagement with the spring contact arms 59 and 60 so that the motor circuit is maintained intact through the contact arms 59 and the conducting ring until the succeeding segment 55 moves into engagement with the spring contact arm 59. The segments 54 and 55 are spaced apart 45° and as a consequence the second movement of the conducting ring, as well as the valve V, is through an arc of 45°. In this new position of the valve V its port 38 now effects communication between the pipe 30 and the exhaust pipe 42 so that the burnt gases are free to exhaust from the barrel section 15 and the pipe 30. When all of the burnt gases have been discharged, the pressure drops to the zero point, thereby causing the hand 64 to engage the contact 62 and thus again restoring the motor circuit so as to initiate operation of the motor. This operation is continued by movement of the segment 55 out of engagement with the spring contact arms and until the ring 52 occupies a position in which the segment 53 moves into engagement with the pressure contact arm 59 when the motor circuit again is disrupted. It will be clear from the arrangement of the segments 53 and 55 that both the ring 52 and the valve V move through an arc of 270° which is sufficient to return the two to the original positions shown in Fig. 1. This completes the cycle of operation for the lowermost pumping unit during which oil from the barrel section 15 has been displaced and delivered to the barrel 22 of the next pumping unit above. As previously described, descension of the float 27 functions to permit closing of the valve 24 so that further supply of pressure fluid to the barrel section 15 is temporarily prevented and that the subsequent operation of the lowermost pumping unit is temporarily stopped.

Under the continued operation of the valve V the gaseous mixture delivered to the pipe 30 is conducted to the barrel section 22 through the branch pipe 35, it being understood that the valve for this barrel section has been previously opened through elevation of its corresponding float by the oil forced from the barrel section 15. As in the first cycle of operation, the pressure of the gas mixture builds up until the pressure gauge functions to complete the motor circuit, thereby turning the valve V to closed position, completing the ignition circuit so as to produce a spark, and thus effecting ignition of the gaseous charge which functions to expel the oil from the barrel section 22 upwardly and to the barrel section 31 after the exhaust of the burnt gases from the barrel section 22 and the pipe 30. The corresponding inlet valve is permitted to close through lowering of the corresponding float, thereby completing the operation of the second pumping unit. In this manner the other pumping units are successively operated until the body of oil initially supplied to the lowermost pumping unit has been successively elevated from one pumping unit to another and finally discharged through the pipe 34 from the barrel section 33. Following

this sequence of operation, the continued rotation of the valve V and the conducting ring 52, again sets the lowermost pumping unit into operation, and this operation is followed by the successive operation of the other pumping units, thereby resulting in the elevation and discharge from the well of a second body of oil. It will be understood that the second body of oil is automatically supplied to the lowermost pumping unit by virtue of the fact that such unit is submerged in the oil.

Referring now to Fig. 2, I have here shown a slightly modified form of pump which is identical with the form shown in Fig. 1, with the exception that a pipe 70 is provided of sufficient diameter and length to completely house the pumping units, its lower end being closed by a head 71 and its upper end communicating with a pipe 72 which corresponds to the pipe 30 and is adapted to conduct the gaseous mixture from the valve V to the pipe 70 and from the latter to the several barrel sections in the same sequence as described in connection with the first pump. In this modification the barrel sections of the pumping units indicated at 73 are connected with one another by tubes 74 which correspond to the tubes 19. The lowermost barrel section is likewise provided with a tube 74 which extends through the head 71 and into the oil in the well. Its lower end is provided with a valve 75 which corresponds to the valve 17.

It is desirable, although not necessary, that each pumping unit be provided with a relief valve for relieving the barrel section of any pressure which may develop therein while the oil is entering the section. In Fig. 3 I have shown the barrel section of a pumping unit provided with such a relief valve, and in the present instance the valve indicated at 76 is formed on the end of the stem of the gas inlet valve 24 so that according as the gas valve is opened or closed, the relief valve will be closed or opened. In the open position of the relief valve it permits venting of air to the atmosphere through a port 78, thus relieving the barrel section of any internal pressure.

Although I have herein shown and described only two forms of oil well pumps embodying my invention, it is to be understood that various changes and modifications may be made herein without departing from the spirit of the invention and the spirit and scope of the appended claims.

55 I claim:

1. A pump adapted for pumping liquid from a well and comprising a barrel, provided with a valve-controlled liquid inlet, a valve-controlled liquid outlet, and a valve-controlled fluid inlet; means adapted to supply charges of a combustible fluid under pressure to the fluid inlet in the barrel from a suitable source of supply; ignition means connected in circuit with a source of electric energy and adapted by the closing of its circuit to ignite

the charges of fluid in the barrel; a motor connected in circuit with the source of electric energy; a valve adapted to be operated by the motor and connected in circuit with the source of electric energy; and a pressure gauge connected with the fluid-supply means so as to register a zero pressure or a predetermined pressure above zero of the fluid and connected with the valve and motor circuit, thereby closing the valve and motor circuit only when the gauge indicates the zero pressure or the predetermined pressure above zero, and thus causing the motor to move the valve to different positions, the construction and arrangement of the valve being such that in one position the valve will allow the combustible fluid to pass therethrough to the fluid inlet in the barrel, that in a succeeding position the valve in the mechanism will shut off communication between the barrel and the fluid supply and simultaneously will cause the closing of the circuit for the ignition means so as to ignite the charge of the combustible fluid within the barrel and thereby to expel liquid from the barrel through the liquid outlet, and that in a third succeeding position the valve will allow the exhaust of the burnt gases from the barrel to the atmosphere.

2. A pump adapted for pumping liquid from a well and comprising a barrel provided with a valve-controlled liquid inlet, a valve-controlled liquid outlet, and a valve-controlled fluid inlet; means adapted to supply charges of a combustible fluid under pressure to the fluid inlet in the barrel from a suitable source of supply; ignition means connected in circuit with a source of electric energy and adapted by the closing of its circuit to ignite the charges of fluid in the barrel; a motor connected in circuit with the source of electric energy; a valve adapted to be operated by the motor and connected in circuit with the source of electric energy; a pressure gauge connected with the fluid-supply means so as to register a zero pressure or a predetermined pressure above zero of the fluid and connected with the valve and motor circuit, thereby closing the valve and motor circuit only when the gauge indicates the zero pressure or the predetermined pressure above zero, and thus causing the motor to move the valve to different positions, the construction and arrangement of the valve being such that in one position the valve will allow the combustible fluid to pass therethrough to the fluid inlet in the barrel, that in a succeeding position the valve will shut off communication between the barrel and the fluid supply and simultaneously will cause the closing of the circuit for the ignition means so as to ignite the charge of the combustible fluid within the barrel and thereby to expel liquid from the barrel through the liquid outlet, and that in a third succeeding position the valve will allow the exhaust of the burnt gases from the barrel

to the atmosphere; and means controlled by the flow of liquid in the barrel so as to open the valve at the fluid inlet when the barrel is comparatively full of liquid and to allow the valve at the fluid inlet to close when the liquid has been expelled from the barrel.

3. A pump adapted for pumping liquid from a well and comprising a barrel provided with a valve-controlled liquid inlet, a valve-controlled liquid outlet, a fluid inlet, and a relief port leading from the interior of the barrel to the atmosphere; means adapted to supply charges of a combustible fluid under pressure to the fluid inlet in the barrel from a suitable source of supply; ignition means connected in circuit with a source of electric energy and adapted by the closing of its circuit to ignite the charges of fluid in the barrel; a motor connected in circuit with the source of electric energy; a valve adapted to be operated by the motor and connected in circuit with the source of electric energy; a pressure gauge connected with the fluid-supply means so as to register a zero pressure or a predetermined pressure above zero of the fluid and connected with the valve and motor circuit, thereby closing the valve and motor circuit only when the gauge indicates the zero pressure or the predetermined pressure above zero, and thus causing the motor to move the valve to different positions, the construction and arrangement of the valve being such that in one position the valve will allow the combustible fluid to pass therethrough to the pumping units, that in a succeeding position the valve will shut off communication between the pumping units and the fluid supply and simultaneously will cause the closing of the circuit for the ignition means so as to ignite the charge of the combustible fluid within a pumping unit and thereby to expel liquid therefrom into an adjacent unit, and that in a third succeeding position the valve will allow the exhaust of the burnt gases from the respective units to the atmosphere.

25 to 30

35 to 40

45 to 50

55 to 60

65 to 70

cuit to ignite the charges of fluid in the pumping units; a motor connected in circuit with the source of electric energy; a valve adapted to be operated by the motor and connected in circuit with the source of electric energy; a pressure gauge connected with the fluid-supply means so as to register a zero pressure or a predetermined pressure above zero of the fluid and connected with the valve and motor circuit, thereby closing the valve and motor circuit only when the gauge indicates the zero pressure or the predetermined pressure above zero, and thus causing the motor to move the valve to different positions, the construction and arrangement of the valve being such that in one position the valve will allow the combustible fluid to pass therethrough to the pumping units, that in a succeeding position the valve will shut off communication between the pumping units and the fluid supply and simultaneously will cause the closing of the circuit for the ignition means so as to ignite the charge of the combustible fluid within a pumping unit and thereby to expel liquid therefrom into an adjacent unit, and that in a third succeeding position the valve will allow the exhaust of the burnt gases from the respective units to the atmosphere.

75 to 80

85 to 90

95 to 100

5. A pump comprising a plurality of pumping units adapted to be arranged one above another within a well and to pump liquid from the latter; means adapted to supply charges of a combustible fluid under pressure to the pumping units from a suitable source of supply; ignition means connected in circuit with a source of electric energy and adapted by the closing of its circuit to ignite the charges of fluid in the pumping units; a motor connected in circuit with the source of electric energy; a valve adapted to be operated by the motor and connected in circuit with the source of electric energy; a pressure gauge connected with the fluid supply means so as to register a zero pressure or a predetermined pressure above zero of the fluid and connected with the valve and motor circuit, thereby closing the valve and motor circuit only when the gauge indicates the zero pressure or the predetermined pressure above zero, and thus causing the motor to move the valve to different positions, the construction and arrangement of the valve being such that in one position the valve will allow the combustible fluid to pass therethrough to the pumping units, that in a succeeding position the valve will shut off communication between the pumping units and the fluid supply and simultaneously will cause the closing of the circuit for the ignition means so as to ignite the charge of the combustible fluid within a pumping unit and thereby to expel liquid therefrom into an adjacent unit, and that in a third succeeding position the valve will allow the exhaust of the burnt gases from the respective units to the atmosphere.

105 to 110

115 to 120

125 to 130

4. A pump comprising a plurality of pumping units adapted to be arranged one above another within a well and to pump liquid from the latter; means adapted to supply charges of a combustible fluid under pressure to the pumping units from a suitable source of supply; ignition means connected in circuit with a source of electric energy and adapted by the closing of its circuit

will allow the exhaust of the burnt gases from the respective units to the atmosphere; valve means provided in each of the pumping units for controlling the delivery of fluid to the unit; and means controlled by the flow of liquid in the pumping units so as to cause operation of the valve means in the respective units and thereby to supply the combustible fluid to the pumping units successively upward from the lowermost unit.
